FILTER-UNIT ATTACHMENT FOR TOBACCO PIPES

Filed Aug. 12, 1937

UNITED STATES PATENT OFFICE

2,169,730

FILTER-UNIT ATTACHMENT FOR TOBACCO
PIPES

Edward H. Lange, Baltimore, Md.

Application August 12, 1937, Serial No. 158,812

15 Claims. (Cl. 131—202)

This invention relates to tobacco-pipes, and more particularly to a unit readily attachable to a pipe without the use of screws or pins through any thin walled portion of the pipe, or in any part of the body of the pipe, and by means of which a suitable filter-unit can be readily inserted and ejected, at a location in the pipe yielding the greatest advantages in maintaining a clean smoke-transmission conduit to the mouth-piece, and in simplicity and cleanliness of operation in renewing a filter-unit, and by means of which the handling of a used filter-unit is eliminated, together with the necessity for detaching tar-coated parts of the pipe.

Certain advantages of a renewable filter-unit in direct contact with the tobacco in the tobacco-bowl, at the bottom of a charge of tobacco and immediately before the entrance to the smoke transmission conduit, together with a plane-surface pivoted member permitting a non-binding means for covering and uncovering, and insertion and ejection of the filter-unit, have been previously pointed out in my U. S. Patent application, Serial No. 11,980, and an object of this invention is to apply these principles in an improved form of filter-unit attachment which can be readily manufactured by machine processes, and attached to a pipe without the necessity of using pins or screws into the body of the pipe; and further to apply these principles in an improved form of filter-unit for the filter-unit attachment, which lends itself readily to machine processes of manufacture.

A further object of this invention is to provide a filter-unit which can only be inserted into the filter-unit attachment in one way, and having an index at the bottom of the filter-unit indicating the proper manner of insertion, and by means of which an opening of the filter-unit is made to register with an opening of the smoke-transmission conduit.

These objects and others, will be better understood by reference to the accompanying drawing and the following specification, and are further pointed out in the appended claims.

Referring to the drawing, Fig. 1 shows a plan-view of a T-shaped member from which a part of the filter-unit attachment is formed.

Fig. 2 shows the T-shaped member after it has been formed into a cylindrically-shaped expandable member with a projection, a central sectional view being shown.

Fig. 3 shows another view of Fig. 2, from the top of the cylindrically-shaped expandable member.

Fig. 4 shows a side view of the cover-member for covering the bottom of the tobacco-pipe.

Fig. 5 shows a plan-view of the cover-member of Fig. 4.

Fig. 6 shows a side view of the assembly of the filter-unit attachment, with the cover-member pivotally attached to the projection.

Fig. 7 shows a plan-view of the bottom of a tobacco-pipe, prepared for insertion of a filter-unit attachment.

Fig. 8 shows a side-view of the assembled pipe, with a vertical section of the tobacco-bowl member, and a filter-unit attachment and filter-unit inserted.

Fig. 9 shows a plan-view of the bottom of the pipe, with a filter-unit attachment inserted.

Fig. 10 shows a side-view of part of a strip of liquid-absorbent material, and of the spacer-strip.

Fig. 10a shows an end-view of the strip of liquid-absorbent material, and of the spacer-strip.

Fig. 10b shows these strips after being spirally-wound, and in a side view.

Fig. 10c shows a plan-view of a gasket-member.

Fig. 6a shows a side-view of a complete assembly, of the filter-unit attachment, with the filter-unit inserted.

Referring to Figs. 1, 2, 3, and 6, at 2a and 2b are parts of a T-shaped member, preferably of sheet metal. The lower edges of the part 2a, may be tapered, as shown by the angle 2d, so that when the part 2a is formed into a cylindrically-shaped member, the lower edges 2k are in the same plane as the part 2b, which part is bent 35 as shown to form a projection. By this means, even though the axis 2g, which is coincident with the axis of the tobacco-bowl is inclined to the plane 2f, the edges 2k are parallel to the plane 2f, which plane is parallel to the bottom 40 plane of the tobacco-pipe, shown at 10a, Fig. 7. At 6c is an orifice, for registering with the opening 6b of the smoke-transmission conduit 6a into the side of the hole 2 through the bottom of the tobacco-bowl member 6, Fig. 7, and 8. At 45 2c is a rivet-hole, one side of the hole being counter-sunk, as illustrated at 2e. When the part 2a is formed into a cylindrically-shaped member, a small gap 2h remains, and by this means the relatively stiff sheet metal cylinder 50 permits a contraction in diameter by means of lateral pressure upon 2a, and can be inserted into the hole 2, after which it binds itself tightly within the hole 2.

Referring to Figs. 4, 5, 6, and 6a, at 4a is a 55

cover-member for the bottom plane $10a$ of the tobacco-pipe, and having the enlargement 4 , for covering the part of the bottom plane immediately below the hole 2 through the bottom of the tobacco-bowl, as shown in Fig. 7. At $4d$ is another rivet-hole, for registering with the rivet-hole $2c$, the member $4a$ being riveted to the projection $2b$ by means of the rivet 5 , which has a relatively thin head, and a riveted portion $5a$ within the countersunk part $2e$ of the hole $2c$. At $4c$, is a small indentation, and at $4b$ is a corresponding small projection.

Referring to Figs. 7, 8, and 9, a straight-stem tobacco-pipe is shown, having a tobacco-bowl member 6 , a smoke-transmission conduit $6a$, a smoking-stem 7 with conduit $7b$ connected with the smoke-transmission conduit $6a$, a mouth-piece $7d$, and a hole 2 , through the bottom of the tobacco-bowl. The bore $8a$ of the tobacco-bowl 1 , is slightly larger than the hole 2 , as shown, and may be tapered. The effective bore is determined as shown, by the layer of carbon 8 , which results after use of the pipe. The only preparation of the tobacco-pipe necessary for use with the filter-unit attachment is illustrated in Fig. 7. At 11 and $11c$ is shown a part of the normal bottom plane of a straight-stem pipe, the plane 11 normally extending up to the bottom of the tobacco-bowl 1 , in a pipe not prepared for use with the filter-unit attachment. By means of an abrasive-wheel, or otherwise, the plane $10a-10$ is cut, parallel to $11-1c$, and of sufficient depth into the pipe to accommodate the thickness of the cover-member $4a$, so that the bottom of $4a$ is coplanar with $11-1c$ when the filter-unit attachment is in position. A hole 2 is cut through the bottom of the tobacco-bowl and through the plane $10a-10$. At $10c$ is a groove countersunk into the body of the tobacco-bowl member, for accommodating the projection $2b$. This groove is preferably countersunk slightly deeper than the thickness of the projection $2b$. By this means the small bending moment exerted upon the member $2b$ causes the cover-member $4a$ to be pulled down tightly against the plane $10a-10$. A small indentation at $10b$, serves to accommodate the projection $4b$, and to hold the cover-member in a position normally covering the bottom of the hole 2 . The lower edge $2k$ serves as a ledge, against which a gasket-member illustrated in Fig. 10c, may be pressed by the cover-member $4a$. A conventional smoking-stem 7 is attached to the tobacco-bowl member 6 , as illustrated at $7a$.

Among the advantages of this form of filter-unit attachment are the simplicity of the structure for securing and maintaining a tightly fitting cover-member, without recourse to screws or pins into the body of the pipe. As the smoke-transmission conduit is usually a thin-walled structure, there is little material for securing and maintaining a tight pivot by screws or pins, and such resilience as is attainable with a screw pivot may result in stripping the screw-threads. The form of attachment here disclosed can be readily removed, if desired, without mutilation of the structure of the tobacco-bowl member. The frictional pressure of the expansible member against the sides of the hole 2 can be readily adjusted, and the corresponding pressure of the cover-member against the plane $10a-10$, by reason of the slightly greater depth of the groove $10c$ than the thickness of the projection $2b$. The cover-member may be finished with any metal plating desired, and when finished with a natural wood coating the attachment present a minimum

deviation in appearance from conventional forms of tobacco-pipe.

Referring to Figs. 10, 10a, 10b, and 10c, part of a strip of liquid-absorbent material, is illustrated at 9 , Fig. 10, and at $9f$ is a spacer-strip, preferably of the same material, and obtained by folding over a part of the strip 9 , as shown. If desired, however, a separate strip of liquid-absorbent material may be used for the spacer-strip. The liquid-absorbent material of the strips may be for example, a highly absorbent paper. The thickness indicated in Fig. 10a, is only for purposes of illustration, and is preferably much thinner than illustrated, in order to secure a large number of convolutions within the available inside diameter of the expansible member $2a$. At $9a$, are perforations through the strip 9 . The strip 9 , is spirally-wound, the spacer-strip $9f$ being concentrically spirally-wound along with 9 , and the end $9m$ of the outermost convolution is secured to the adjacent convolution to hold the convolutions in a tightly wound condition, for example by an adhesive at the edge $9m$. The spacer-strip thus provides an annular bottom for the spiral convolutions, above which there are numerous channels between the walls of the strip 9 . Another important feature of the filter-unit is the modified spacing of the perforations $9a$, to accomplish a peripheral displacement of the perforations for a group of outer convolutions, so that for the outer group of convolutions, a perforation of any convolution is peripherally displaced in relation to the corresponding perforation of the adjacent convolution. The number and size of perforations shown, is only for purposes of illustration, it being understood that the perforations can be arranged so that there are for example, one, or two, or more per convolution. Whatever the number, the spacing is modified so that there will be a peripheral displacement. This is illustrated, for example in Fig. 10b, one of the perforations of the adjacent inner convolution being evident through the perforation $9a$ of the outermost convolution; a preferred amount of peripheral displacement however being such that perforations of adjacent convolutions of an outer group of convolutions do not register with each other. By this means the number of curved paths through which a mixture of tobacco-particles, tobacco-tar, and tobacco-smoke must pass before emerging from the filter-unit into the smoke-transmission conduit is greatly increased, and the efficiency of the filter increased correspondingly.

Such a modification of spacing, as illustrated for example at $9g$, $9h$, and $9i$, is obtainable in various ways; it may be obtained for example by drawing a paper tape with spacer-strip under a punch, the paper tape and spacer-strip being spirally-wound and advancing the unwound portion during the released part of the punch-stroke. A perforation may be determined, for example, every half revolution of the spiral convolution, that is, during each release stroke of the punch the spiral winding may be advanced a half revolution. Because of the increasing diameter of the spiral winding, caused by the spacer-strip and paper tape, a perforation will be wound upon a larger circumference than the circumference which initially determined the spacing of the perforation; a displacement of the perforations can thus be obtained, or by otherwise modifying the amount of advance of the spiral winding for each release stroke of the punch, and in relation to

the number of turns or convolutions of the spiral winding.

At 9c, Fig. 10c, is shown a gasket-member. The gasket-member is preferably of liquid-absorbing material, for example blotting-paper, and has a notch 9k, the width of the projection 2b, and having a depth equal to the thickness of 2b, so as to accommodate the projection 2b. The gasket-member 9c fits into the bottom of the hole 2, and between the edge 2k and the enlargement 4 of 4a, as illustrated in Fig. 6a. The gasket-member may be used to seal the bottom of the hole 2, whether or not a filter as illustrated in Fig. 10b is used. This arrangement provides easy access to the bottom of the pipe for cleaning, when used in this manner.

A preferred arrangement, however, giving the best mode of application of this invention, consists in using both the gasket-member 9c and the filter 9, and preferably with the filter 9 attached to 9c, so that one of the perforations 9a of the outermost convolution is nearest to the notch 9k, and registers with 9k. With this arrangement, the filter will always be properly inserted into 2a, since there is only one way the gasket-member fits into the bottom of the hole 2. By attaching the gasket-member to the bottom of 9, for example with adhesive applied at a portion of 9c opposite the notch 9k, a complete filter-unit is obtained, and 9c is sufficiently free to accommodate itself to the small angular displacement of the axis of the tobacco-bowl from the vertical.

It will be evident that with the invention here disclosed, the filter-unit attachment provides the necessary tightness of fit of the cover-member, without recourse to screws or pins through the body of the tobacco-pipe, and that the necessary degree of tightness can be readily maintained, and if desired adjusted, by axial displacement 40 of the member 2a which is tightly held by friction within the hole 2. In operation, a used filter-unit is readily ejected without the necessity of dismembering the pipe, and without the necessity of handling tar-coated parts, and of further cleaning of ducts. To eject a used filter-unit, the pipe is held over an ash receiver, the cover-member 4a displaced, and the used filter-unit pushed out through the bottom by means of a match-stick, for example.

While I have shown and described certain forms and arrangements of parts, to illustrate my invention, it will be evident that numerous changes can be made, and within the spirit of my invention as further set forth in the 55 pended claims.

What is claimed is:

1. A filter-unit attachment in combination with a tobacco-pipe having a tobacco-bowl member, a hole through the bottom of the tobacco-bowl, and 60 a smoke-transmission conduit opening into the side of said hole, said filter-unit attachment having an expandable member for tightly and concentrically fitting said hole, an orifice for registering with the said opening of the smoke-transmission conduit into said hole, and a pivoted member pivotally fastened to said expandable member, for readily covering and uncovering the bottom of said hole.

2. In a tobacco-pipe having a tobacco-bowl member, a hole through the bottom of the tobacco bowl, and a smoke-transmission conduit opening into the side of said hole, a filter-unit attachment having an expandable member tightly and concentrically filtering said hole, a 70 projection connected with said expandable mem-

ber and countersunk into the tobacco-bowl member, an orifice in said expandable member registering with the said opening of the smoke-transmission conduit into said hole, a pivoted member pivotally fastened to said projection, for readily covering and uncovering the bottom of said hole, and means for holding said pivoted member in a position normally covering said hole. 5

3. In combination with claim 2, a filter-unit for said filter-unit attachment, said filter-unit 10 having a gasket-member concentrically fitting the bottom of said hole, between the pivoted member and the expandable member, a notch in said gasket member registering with said projection, a liquid-absorbing structure concentrically fitting said expandable member, directly contacting the tobacco in the tobacco-bowl, and having a multiplicity of indirect passages leading from the tobacco to said orifice independent of inherent small openings throughout the material of said liquid-absorbing structure, and a fastening means for securely fastening the gasket-member to said liquid-absorbing structure. 15

4. In combination with claim 2, a filter-unit 20 for said attachment, for concentrically fitting said expandable member, for directly contacting the tobacco in the tobacco-bowl, and for extending across said orifice, said filter-unit having a spirally-wound liquid-absorbent strip, a concentrically spirally-wound spacer-strip of smaller width than the liquid-absorbent strip, a series of perforations in the liquid-absorbent strip so spaced that for the outer convolutions of the spiral of the liquid-absorbent strip the perforations of any convolution are peripherally displaced in relation to the perforations of an adjacent convolution, and binding means for binding the end of the outermost convolution to an adjacent convolution. 25

5. In combination with claim 2, a gasket-member for said attachment, for concentrically fitting said hole, between the pivoted member and the expandable member, said gasket-member having a notch for registering with said projection. 35

6. In a tobacco-pipe having a tobacco-bowl member, a hole through the bottom of the tobacco-bowl and a smoke-transmission conduit opening into the side of said hole, a filter-unit attachment having an expandable member tightly 50 and concentrically fitting said hole, a projection connected with said expandable member and countersunk into the tobacco-bowl member, an orifice in said expandable member registering with the said opening of the smoke-transmission conduit into said hole, a pivoted member pivotally fastened to said projection for readily covering and uncovering the bottom of said hole, a holding means for holding said pivoted member in a position normally covering said hole, and a filter-unit 55 in said filter-unit attachment; said filter-unit having a spirally-wound liquid-absorbent strip, a concentrically spirally-wound spacer-strip of smaller width than the liquid-absorbent strip, a series of perforations in the liquid-absorbent strip so spaced that for the outer convolutions of the spiral of liquid-absorbent strip the perforations of any convolution are peripherally displaced in relation to the perforations of an adjacent convolution, binding means for binding the end of the outermost convolution to an adjacent convolution, and a gasket-member between the pivoted member and said expandable member. 65

7. In a tobacco-pipe with a tobacco-bowl, a 70 projection connected with said expandable mem-

ber and countersunk into the tobacco-bowl member, an orifice in said expandable member registering with the said opening of the smoke-transmission conduit into said hole, a pivoted member pivotally fastened to said projection, for readily covering and uncovering the bottom of said hole, and means for holding said pivoted member in a position normally covering said hole. 75

- hole through the bottom of said bowl and a smoke-transmission conduit opening into said hole, a filter-unit attachment, said attachment having a cylindrically-shaped member for concentrically fitting the hole through the bottom of the tobacco-bowl, said member having an orifice for registering with said opening of the smoke-transmission conduit into said hole, and a projection; and a pivoted member pivotally attached to said projection, for covering and uncovering the bottom of the tobacco-bowl.
8. A filter-unit for tobacco-pipes, said filter-unit having a spirally-wound liquid-absorbent strip, a concentrically spirally-wound spacer-strip of smaller width than the liquid-absorbent strip, forming a closed end along one edge of the spiral convolutions, a series of perforations along the liquid-absorbent strip and through said strip, so spaced that for the outer convolutions of the spiral of liquid-absorbent strip the perforations of any convolution are peripherally displaced in relation to the perforations of an adjacent convolution, whereby a mixture of tobacco-smoke and tobacco-liquid is constrained to flow along a multiplicity of axial paths between the convolutions, and along a multiplicity of radial paths between the convolutions, before emerging from the filter-unit.
9. In combination with claim 7, a filter-unit insertable into said cylindrically-shaped member through the bottom of said member, and having a gasket-member capable of being covered and firmly held against the bottom of said cylindrically-shaped member by said pivoted member, for sealing the bottom of the tobacco-pipe.
10. In combination with claim 7, a filter-unit insertable into said cylindrically-shaped member from the bottom of said member, capable of direct contact with the tobacco in said bowl, and of absorbing tobacco-liquid and tobacco-particles, and permitting free passage of tobacco-smoke from the tobacco to said orifice, said filter-unit being removable from said cylindrically-shaped member without dismembering the tobacco-pipe.
11. An attachment for tobacco-pipes, said attachment being formed from a T-shaped member, one part of which is formed into an expansible cylinder, the other part of which is formed into a projection, and having a pivoted member pivotally attached to said projection, and an orifice in said expansible cylinder.
12. An attachment for a tobacco-pipe with a tobacco-bowl, a hole through the bottom of the tobacco-bowl and a smoke-transmission conduit opening into said hole, said attachment having a cylindrically-shaped member for insertion into said hole, and a cover-member attached to said cylindrically-shaped member, whereby the bottom of said hole may be readily covered or uncovered without detaching said cover-member.
13. An attachment for a tobacco-pipe having a tobacco-bowl and a hole through the bottom of said bowl, said attachment being formed in part from a T-shaped member, one part of which is formed into an expansible cylinder for fitting said hole, the other part of which is formed into a projection, and a cover-member for said hole permanently attached to said projection.
14. A tobacco-pipe attachment for a tobacco-pipe having a tobacco-bowl, a hole through the bottom of the tobacco-bowl, and a smoke-transmission conduit, said attachment having a sleeve-member for tightly fitting the bottom of said hole, an opening in the wall of said sleeve-member registering with said smoke-transmission conduit for transmitting smoke thereto and a cover-member attached to said sleeve-member, for covering and uncovering the bottom of said hole.
15. A tobacco-pipe having a tobacco-bowl, a hole through the bottom of the tobacco-bowl connected with a smoke-transmission conduit, a sleeve-member capable of being securely held by friction in the bottom of said hole, a cover-member permanently attached to said sleeve-member, for covering and uncovering said hole, and a filter-unit within said sleeve-member, insertable through the bottom of said sleeve-member, and interposed between the tobacco and said smoke-transmission conduit.

EDWARD H. LANGE. 45
